UNITED STATES PATENT OFFICE

LE ROY W. WILLIS, OF STAMFORD, CONNECTICUT, ASSIGNOR TO INTERTYPE CORPORATION, OF BROOKLYN, NEW YORK, A CORPORATION OF NEW YORK

MATRIX FOR TYPOGRAPHICAL MACHINES

Application filed March 17, 1931. Serial No. 523,327.

The present invention relates to matrices for typographical machines, and more especially to those of the kind used in line casting machines of the well known class shown and described in U. S. Patent No. 436,532 granted September 16, 1890 to O. Mergenthaler, wherein the matrices are assembled into lines from which type bars are cast, after which the matrices are returned by distributing mechanism to the magazine or magazines from which they were drawn.

In the operation of modern line casting machines it is usual to employ matrices of a wide variety of sizes ranging for instance from relatively thin ones bearing small newsprint characters to relatively thick ones bearing large heading, advertising or display characters, they being supported while being transported through certain parts of the machine by teeth formed in their upper edges. The handling of the relatively thin light weight matrices bearing the small characters has been generally satisfactory, but the relatively thick matrices bearing the larger size characters have presented certain difficulties due chiefly to their greater weight and thickness, and the presence of their supporting teeth only along an edge thereof and the consequent tendency of such matrices to hang in an inclined position from the ribbed distributor box bar, and the ribbed bar of the second elevator on which the matrices are transported to the distributor box after a slug has been cast. Such hanging of the matrices in inclined position not only caused faulty distribution of the matrices but also rapidly wore their teeth so that such matrices were soon unfit for further use.

These difficulties attending the use of the relatively thick and heavy matrices bearing heading or display characters have been overcome by providing these matrices with relatively wide or long teeth to engage the ribs of the distributor box bar and the matrix transporting bar and thereby maintaining these matrices in upright position thereon, as shown and described in U. S. Letters Patent No. 1,328,146 granted January 13, 1920, to H. R. Freund. Other forms of matrices having special tooth formations have

been proposed to overcome these difficulties, but they could not be used satisfactorily with the usual or standard distributor bar employed in the machines or were otherwise unsatisfactory.

The primary object of the present invention is to further improve the tooth formation of such relatively thick and heavy matrices whereby such matrices will always hang from their teeth in a true vertical position although the teeth are made relatively short or narrow, so that the amount of cutting and the time required to form the teeth are reduced to a minimum and the manufacture of the matrices is facilitated and rendered less expensive than the long or wide teeth hereinbefore referred to, and the arrangement of the teeth on the matrices is such that they will be subjected to minimum stress or wear while the matrices are being transferred to the ribbed bars, such as the second elevator toothed bar, the toothed distributor box bar and the combination distributor bar which successively receive and support the matrices while they are travelling through the machine. Moreover, since the novel arrangement of these narrow teeth avoids hanging of the matrices in an inclined or tilted position while they are travelling through the machine, wear of these narrow teeth is minimized, so that satisfactory length of service is obtainable from these teeth, notwithstanding the narrowness thereof.

In the accompanying drawings:—

Fig. 1 is a perspective view of a matrix having supporting teeth embodying the present invention;

Fig. 2 is a top plan view of the matrix shown in Fig. 1, showing the tooth formation as viewed from above;

Fig. 3 is a rear edge view, partly broken away, of the matrix shown in Figs. 1 and 2;

Fig. 4 is a side elevation of the matrix as viewed from the right in Fig. 3; and

Fig. 5 is an elevation of a portion of the ribbed matrix supporting bar commonly used in line casting machines, showing thereon at the right a matrix having supporting teeth according to the present invention and at

the left a matrix having supporting teeth as previously used.

The matrix M as herein shown is of the general form or outline as that commonly used in line casting machines of the class hereinbefore referred to, such matrices, which are composed usually of brass, comprising a body of approximately rectangular form having lugs or ears projecting from the corners to serve for alining and other purposes in the machine, the rear edge of the matrix body having a character m punched or otherwise formed therein in intaglio, this character forming a die in which the corresponding type character is cast, it being understood that the matrices are commonly assembled in lines with the characters in their rear edges in alinement so that a type bar or slug may be cast against the character bearing portion 20 of the matrices in the line. During the travel of the matrices through the machine, they are suspended from ribbed or toothed rails or bars, such as the second elevator toothed bar, the toothed distributor box bar and the toothed or ribbed combination distributor bar, and for this purpose, the upper edge of each matrix is formed with a V-shaped notch the opposite walls of which are downwardly convergent to receive the toothed or ribbed supporting bar or rail. A portion of one of the usual toothed matrix supporting bars is indicated at 1 in Fig. 5, the lower V-shaped edge of this bar having ribs or teeth 2 with which the teeth in the V-shaped notches of the different matrices engage slidably so that they will be suspended therefrom while travelling therealong.

Heretofore, the relatively thick or large matrices bearing heading, advertising or display characters have been formed with relatively narrow teeth immediately adjacent to and along one side of the matrix, as indicated at m' on the matrix M' in Fig. 5, but since such teeth were entirely at one side of a plane passing vertically through the center of weight of the matrix, such matrix would hang from the matrix supporting bars in an inclined or tilted position as shown in this figure, thereby causing faulty distribution. Furthermore, the inclined position of such matrices while travelling along the toothed or ribbed supporting bars subjected the teeth thereof to rapid wear so that such matrices were prematurely rendered unfit for further use.

Such difficulties have been overcome by providing these relatively thick or large matrices with relatively wide or long teeth, as shown and described in the Freund patent referred to above, and while this has proven very satisfactory in service, it has been found that the amount of cutting necessary to form these long teeth can be reduced to a large extent and thereby effect economy and save time in manufacture and at the same time

produce matrices with narrow teeth which will not wear out quickly as heretofore.

The present invention provides an improved tooth formation for such relatively thick and heavy matrices whereby the true vertical or upright suspension of these matrices from the toothed or ribbed supporting bars in the machine is attained and yet the supporting teeth of the matrices are relatively narrow or short so that the accurate cutting of the teeth may be accomplished more rapidly and at less expense than is possible with the relatively wide or long teeth, the suspension of the matrices in true vertical or upright position, accomplished by a novel arrangement of the teeth, minimizing wear thereon so that satisfactory length of service is obtainable from narrow or short teeth.

According to the present invention, the supporting or combination teeth m^2 and m^3 on the opposite convergent walls of the V-shaped notch in the upper end of the matrix are dissimilar in their locations or positions. The row of teeth m^2 extend in a vertical plane parallel to and are immediately adjacent to the flat face m^4 of the matrix, which is the rear or following face of the matrix while it is travelling along the combination distributor bar for distribution; these teeth extending from the apex to the top of the V-shaped notch. The teeth m^3 however on the other wall of the V-shaped notch extend in a row in an inclined plane or obliquely from the apex of the V-shaped notch at a point immediately adjacent to the face m^4 of the matrix, upwardly toward the opposite flat face of the matrix as these teeth approach the top of the V-shaped notch, and preferably, the teeth m^3 at or near the top of the V-shaped notch lie in or extend across or beyond a plane passing vertically through the center of weight of the matrix. Both sets of teeth m^2 and m^3 are narrow or of short length comparable with the narrow or short teeth previously used generally on matrices, so that the operation of cutting or broaching the improved teeth can be accomplished as quickly and inexpensively as the usual narrow or short teeth, and to facilitate the cutting of the teeth, they are all preferably of uniform width or length, as shown.

By arranging the teeth on one wall of the notch, as the teeth m^2 , parallel and immediately adjacent to the face m^4 of the matrix, dropping of the matrix when it reaches the precisely correct point in the length of the combination distributor bar is insured when these matrices are used in a machine having the usual or standard distributor bar, since these teeth lie in the plane of distribution for the respective matrices as established by the combinations of teeth on the usual or standard distributor bar, and by extending the teeth on the opposite wall of the V-shaped notch, as the teeth m^3 , obliquely to or across

a plane passing vertically through the center of weight of the matrix, the matrix will be suspended by the teeth m^2 and m^3 from the ribs of the toothed supporting bars in 5 the machine at points which lie approximately in a plane passing vertically through the center of weight of the matrix, so that the matrix will hang in a true vertical or upright position while travelling along the supporting bars, as shown diagrammatically by 10 the right hand matrix M in Fig. 5. This vertical or upright suspension of the matrix from the toothed supporting bars while travelling therealong will insure correct distribution, and, moreover, the supporting of the matrix in a true upright position while travelling along the toothed or ribbed supporting bars in the machine, will minimize wear between the matrix teeth and the teeth or ribs 15 of the supporting bars in the machine, so that satisfactory length of service is obtainable from matrices having relatively narrow or short teeth when arranged or disposed in accordance with the present invention as 20 hereinbefore described.

The oblique arrangement of the teeth at one side of the notch in the matrix presents the further advantage of causing a successive engagement of these teeth with the ribs 25 or teeth at the entrance ends of the second elevator toothed bar, the toothed distributor box bar and the combination distributor bar, and any slight wear of the teeth or ribs or slight misalignment of these ribbed supporting bars with respect to one another will not cause all of the teeth of the matrix to simultaneously come into engagement therewith but will cause a successive threading of the teeth, one at a time, upon these ribbed or 30 toothed bars, thus avoiding undue wear of the teeth and avoiding obstruction to the matrices at the points where they are transferred to the toothed or ribbed supporting bars during the passage of the matrices 35 through the machine.

It will be understood that in the manufacture of matrices having teeth constructed and arranged according to the present invention, the top of the matrix, at the side opposite to that in which the teeth are formed, 40 is cut away to form the yoke-shaped recess m^5 as usual, and the convergent walls of the V-shaped notch alongside of the teeth thereon are cut away so that the broaching or milling 45 operation used in cutting the teeth is reduced to the width of the teeth, thus enabling such operation to be performed rapidly and with accuracy and at less expense than is possible with relatively wide or long teeth. The 50 weight of the relatively thick matrix may be reduced by drilling or otherwise forming a hole m^6 therein.

It will be further understood that the arrangement of the teeth on matrices as herein 55 described may be varied in many ways to ac-

complish the results generally aimed at by the preferred construction illustrated in the drawings, the essence of the invention residing in the provision of narrow teeth which, from the apex of the notch to the top, will all 70 have their leading edges, at least on one side of the notch, extend obliquely from one side of the matrix substantially to or through the center of weight or toward the opposite side of the matrix. 75

I claim as my invention:

1. A matrix for typographical machines having a notch with convergent walls, and distributor teeth on said walls, the teeth on one of said walls lying in a vertical plane parallel to a side of the matrix and the teeth on the other wall extending obliquely across a portion of said wall and through the center of weight of the matrix. 80

2. A matrix for typographical machines having a notch with convergent walls, and distributor teeth on said walls, the teeth on one of said walls lying in a vertical plane parallel and adjacent to a side of the matrix and the teeth on the other wall extending from said side of the matrix obliquely toward the center of weight of the matrix. 90

3. A matrix for typographical machines comprising a body having a notch with convergent walls, and distributor teeth on said walls, the leading edges of the teeth on one of said walls lying parallel to a side of the matrix body and the leading edges of the teeth on the other wall extending obliquely across a portion of said wall from the apex 100 to the top of the notch. 95

4. A matrix for typographical machines comprising a body having a notch with convergent walls, and distributor teeth of uniform length on said walls, the leading edges 105 of the teeth on one of said walls lying parallel and adjacent to a side of the matrix body, and the leading edges of the teeth on the other wall extending obliquely from the apex of the notch toward the opposite side of the 110 matrix.

5. A matrix for typographical machines comprising a body having a notch with convergent walls, and distributor teeth of uniform length on said walls, the teeth on one 115 of said walls lying parallel and adjacent to a side of the matrix body, and the teeth on the other wall extending obliquely from said side of the matrix body and from the apex 120 of the notch to the center of weight of the matrix.

In testimony whereof I have hereunto set my hand.

LE ROY W. WILLIS.
